UNITED STATES PATENT OFFICE

104,487

DESIGN FOR A SUITCASE

Elmer Ellsworth Wilt, Chicago, Ill.

Application April 6, 1937, Serial No. 68,586

Term of patent 14 years

To all whom it may concern:

Be it known that I, Elmer Ellsworth Wilt, a citizen of the United States, residing at Chicago, in the county of Cook and State of Illinois, have invented a new, original, and ornamental Design for a Suitcase, of which the following is a specification, reference being had to the accompanying drawing forming part thereof.

In the drawing:

The figure is a perspective view of a suitcase showing my new design.

I claim:

The ornamental design for a suitcase as shown.

ELMER ELLSWORTH WILT.
